REFRIGERATING APPARATUS

Albert O. Grooms, Dayton, Ohio, assignor to General Motors Corporation, Dayton, Ohio, a corporation of Delaware

Application October 30, 1936, Serial No. 108,377

12 Claims. (Cl. 200—83)

This invention relates to refrigerating apparatus and more particularly to control means therefor.

Heretofore, low differential switches for refrigerating systems and temperature controls mainly have had bimetal as the actuating element. Bimetal switches, because of their low contact pressures, can ordinarily carry only a small amount of current at a low voltage. This necessitates the use of a relay in order to control heavier currents.

In refrigerating systems and other temperature controls, it is often desirable to have a more simple arrangement wherein the relay is eliminated and it is usually desired to employ a switch operated by gas pressure. Considerable difficulties are encountered in attempting to make a low differential switch operated by gas pressure. In the first place, the metal bellows, which are ordinarily used in such switches, may in the present state of the art, operate only in a compressed condition to avoid bellows failure. When operating under such conditions the natural spring of the metal bellows tends to increase the minimum differential. Also, because it is usually required that the switch be made small, the spring which opposes the expansion of the bellows must be made rather short and, therefore, have a very high rate. This high rate also tends to considerably increase the minimum differential.

It is an object of my invention to provide a relatively small switch actuated by gas pressure which switch has a small differential and has a relatively high current carrying capacity.

It is another object of my invention to provide a control having means to counteract in whole or in part the tendency of the bellows and the springs to increase the differential of the control.

It is also an object to provide a control means with an additional means for reducing the minimum differential of the switch.

It is a further object of my invention to provide a single means for snuffing out the arc at two sets of contacts in a switch.

It is still another object of my invention to provide a refrigerator control switch having an improved structure and an improved mechanism together with means for preventing condensation of moisture upon and corrosion of the switch parts.

Further objects and advantages of the present invention will be apparent from the following description, reference being had to the accom-

panying drawings, wherein a preferred form of the present invention is clearly shown.

In the drawings:

Fig. 1 is a view partly in section of one form of a refrigerator control switch embodying my invention; 5

Fig. 2 is a section taken along the line 2—2 of Fig. 1;

Fig. 3 is a section taken along the line 3—3 of Fig. 1; and 10

Fig. 4 is a chart showing a diagram of forces in terms of the movement of the bellows lever as well as a temperature pressure scale therefor.

Briefly, I have shown a switch provided with a bellows, a bellows follower lever and a double toggle snap acting mechanism operatively connecting the main switch contacts with the bellows follower lever. A rather short, stiff main spring opposes the expansion of the bellows and maintains the bellows under compression within the range of movement of the bellows and bellows follower lever. A set of manually controllable overload contacts are also provided and a combined electromagnetic blow-out coil and thermal overload heater are provided for snuffing out the arc at both sets of contacts and for providing the thermal overload of the solder pot type. The thermal overload is of the trip-free type. 15

The spring effect of the bellows and the high rate of the main spring tend to make the differential of the switch rather high, for example, about 13° F. This is satisfactory for household refrigerating systems where the bellows is operated according to evaporator temperature. 30

However, if the switch is to be controlled by air temperature, this temperature differential must be reduced. In order to reduce this temperature differential, I connect a tension spring to the bellows follower lever which extends diagonally slightly below the pivot point of the main lever so that it exerts its greatest force when the bellows is collapsed and a constantly decreasing force as the bellows expands. This, therefore, has the effect of a spring with a negative rate and operates to reduce the positive rate of the main spring and the spring effect of the bellows. As shown in Fig. 4, this bellows cancel spring or extra toggle type spring can be so set that it is substantially equal and opposite to the inherent spring of the bellows, but if desired, this angularity and characteristic of its spring may be changed so as to have a greater effect sufficient to reduce the effect of the high rate of the main spring. Through this means the tem- 35

perature differential of the switch may be reduced without changing its size or the limits of movement of the bellows and bellows follower lever.

Referring now to the drawings and more particularly to Fig. 1, there is shown one form of refrigerator control switch embodying my invention. This switch is provided with a case 20 of a molded insulating material such as hard rubber or a phenolic condensation product. This case is provided with a slot 22 which receives the neck of a metal bellows 24. This neck is lodged within the slot 22 of the casing and fastened by a thin nut 26. The interior of the bellows 24 is connected by tubing 28 to the interior of a volatile liquid charged thermostat bulb not shown. A yoke 30 has an aperture which surrounds the neck of the bellows 24 and has a tongue 32 which is turned down in the slot 22 which receives the neck of the bellows. One side of the yoke 30, designated by the reference character 34, receives a pivot pin 36 to which is connected one end of the bellows follower lever 38.

The upper end of the other side of the yoke 30 is notched as indicated by the reference character 40 so that it may be received by the sides of an opening 42 provided in the bellows follower lever 38. This aperture 42 is elongated in the direction transverse to the notched portion 40 so that the notched portion 40 may pass through the aperture 42 when the bellows follower lever 38 is in a position transverse to its proper position. This, therefore, acts somewhat similarly to a bayonet slot arrangement. The notched portion 40, therefore, by its upper and lower shoulders, which are located to engage the edges of the aperture 42 of the bellows follower lever 38 thus limit the movement of the bellows follower 38 and thereby limit the expansion of the bellows 24.

The free end of the bellows follower lever is provided with a pair of notches 44 which receive the chisel-shaped ends of a secondary snap acting lever 46. The secondary lever 46 is generally U-shaped and on its opposite end is provided with a slot which receives a T-shaped member 47 having an aperture therein which receives one end of the tension coil spring 48. The opposite end of this tension coil spring is hooked over a turned up ear 50 provided upon an L-shaped contact carrying lever 52 which is pivoted upon a pivot pin 54 which in turn is supported by a bracket fastened to and extending from the adjacent wall of the switch case 20. This contact lever 52 is provided with portions on either side of the secondary lever 46 which serve as stops to limit the movement of the secondary lever 46.

Part of the contact lever is formed of heavy sheet brass while a second part 56 which is riveted to the brass part is made up of a stiff molded insulating material which preferably contains fabric. The switch contacts 58 are located at the end of the portion 56 and are riveted to a clip 60 which extends around the lower end of the portion 56 and has a tongue extending into an aperture provided in the portion 56 to retain the clip 60. The differential of the snap acting mechanism is determined by the angularity of the contact lever 52 in open and closed position. The angularity of the contact carrying lever 52 is limited by the fixed contact which is carried by the contact post 62 while the open position of the contact carrying lever 52 is limited by a differential screw 64 which is held within a

threaded aperture in the casing and has a pin extending into contact with a portion of the contact carrying lever 52 to limit the opening movement of this lever.

In order to place the bellows 24 under compression and in order to balance the gas pressure within the bellows, I provide a tension coil spring 68 which is connected at one end to the bellows follower lever 38 and its other end to a U-shaped nut 70 which is threaded upon an adjusting screw 72 rotatably mounted at both ends within opposite walls of the casing 20. The one end portion of this screw extends through the casing and is provided on the outside with a temperature regulating knob 74. This temperature regulating knob 74 may be turned to increase or decrease the tension upon the spring 68 and so will increase or decrease the gas pressure required within the bellows 24 to move the switch contacts to open and closed position.

This switch mechanism is also provided with a toggle snap acting single cycle loading device. This includes a finger manipulator 76 which is pivoted to the case 20 upon a pivot pin 78. This finger manipulator is provided with a notch 80 which receives a chisel-shaped end of a link 82 which has its other end received and slidably within a pair of apertures provided in a bracket 84 fastened to the case 20. This bracket is provided with a rounded protrusion against which rests the spring retainer of a small compression type coil spring 86 which is threaded upon a screw 88 having one reduced end portion passing through an aperture in the bracket 84 while the other end portion is provided with a nut 90 and a kerf on the end of the screw.

The link 82 is provided with a slot which receives the spring, the nut and the screw. The kerf end of the screw engages the end of the slot to hold and to prevent the rotation of the screw. A link 92 is connected to a portion of the link 82 and extends downwardly therefrom. This downwardly extending link 92 has a shoulder and a narrow tongue extending downwardly through an aperture in the bellows follower lever 38. When the finger manipulator 76 is turned in a clockwise direction about its pivot 78, the link 92 is moved downwardly so that its shoulder comes into engagement with the flat portion of the bellows follower lever 38 and at the same time the link 82 is pushed across the center line between the pivot pin 78 and the hump on the bracket 84 so that the spring 86 will tend to place an additional force by the throwing of the toggle linkage and the link 92 upon the bellows follower lever. This places an additional load upon the bellows 24 and requires a higher pressure and temperature before the switch may be moved to closed circuit position. When this higher pressure and temperature is attained, the bellows follower lever 38 through the link 92 will push the link 82 across its dead center position to the position shown in Fig. 1 where it is inactive. This is employed in household refrigerators to provide a manually initiated automatically reset defrosting cycle for the purpose of providing a cycle which will remove any frost which may collect on the evaporator.

I have also provided a manual on and off snap acting switch which is actuated by the finger manipulator 102 pivoted upon the pin 104 embedded in the casing 20. This finger manipulator 102 has a metal extension 106 which holds one end of the compression toggle spring 108 provided with pointed spring retainers at each end,

one of which engages one arm of a contact carrying lever 110 pivoted to the casing upon a pivot pin 112. The other arm of this lever 110 has an extension 114 of an insulating material 5 containing fabric and hard rubber or a phenolic condensation product. The extreme end of this portion 114 is provided with a clip 116 having a tongue engaging an aperture in the portion 114 for retaining the clip. This clip surrounds the 10 lower end of the member 114 and is provided with a switch contact 118 which is adapted to cooperate with a stationary switch contact 120 mounted upon a stud 122 which is riveted to a movable insulating wall section 124.

15 This mechanism provides a snap acting manual switch. It is, however, also used as a thermal overload mechanism and has a means for resetting the thermal overload mechanism. In order to do this the casing is provided with a hollow boss 126 extending from the bottom wall in Fig. 1 which receives the shaft 128 of the ratchet wheel 130. This shaft 128 is received within a bushing 132 threaded into the hollow boss 126 and fastened to the shaft 128 by a low melting solder. 20 Threaded onto this threaded bushing 132 is a soft iron core 134 upon which is mounted a coil of wire 136 which with the core serves as an electromagnet as well as a thermal overload heater for heating the solder which holds the shaft 128 of 25 the ratchet wheel. This coil 136 is connected by the conductors 138 and 140 in series with the switch contacts 62, 58, 118 and 120. This electromagnet coil is wound tightly with several layers of wire instead of very loosely as heretofore so 30 that it will not be influenced to any great degree by the temperature of the place wherein the switch is located.

Recently, it has been customary to locate the switch upon the evaporator of a household refrigerator and under such conditions the temperature of the switch may fluctuate considerably. 40 The tight winding prevents this fluctuation of temperature from materially varying the operation of the thermal overload. In addition, this electromagnet sets up a magnetic field which embraces both sets of switch contacts and also furnishes a small supply of heat which maintains the switch at a temperature above the temperature of the atmosphere within the refrigerator so 45 that there will be little or no condensation of moisture or deposit of frost upon the parts of the switch.

The ratchet wheel 130 holds a spring tongue 142 between a pair of teeth. This spring tongue is 50 also fastened to a slidable plate 144 which slides with the arms 146 and 148 of a U-shaped bracket which is fastened to the bottom wall of the case 55. This slide plate also has a hooked end portion 150 which is adapted to engage a portion of the arm 114 when the slide 144 is released by the ratchet wheel. When this projection 150 engages the arm 114, it pivots the arm 114 as well as the arm 110 about their pivot 112 to open the contacts 118 and 120. At the same time it throws 60 the toggle spring 108 across its dead center position so that the finger manipulator 102 is moved to its "off" position.

The slide plate 144 is provided with an arm 154 which is pivoted by the pin 156 to the slide plate. 65 This arm has a curved end portion with a notch that is adapted to be engaged by a depending tongue 158 extending from the metal arm 106 attached to the finger manipulator 102. The arm 154 is pulled to the left as shown in Fig. 1 by a 70 tension coil spring 162 connected at the other

end to the arm 148 while a second spring 164 connects the arm 154 to a remote portion of the arm 146. Thus, when the ratchet wheel 130 releases the slide plate, the slide plate 144 and the arm 154 move to the left in Fig. 1 under the motive power of the spring 162 which is thereby reduced in tension while the spring 164 has its tension increased and thereby raises the arm 154 10 sufficiently so that it will be engaged by the arm 158 upon the finger manipulator 102.

Thus, when the finger manipulator 102 is moved from "off" to "on" position, in this circumstance, the arm 158 will engage the notched end of the arm 154. This will move the arm 154 and the slidable plate 144 to the right as located in Fig. 1 15 and at the same time will cause a portion of the face of the arm 154 to be held against the side of the adjacent portion of the contact carrying lever 52 so that the contacts 58 will be held in the open position while the contacts 118 and 120 are 20 being closed and the spring tongue 142 is moved into engagement with the ratchet wheel. During this time the finger manipulator throws the toggle spring 108 across the dead center position to move the overload contacts into closed position. The contacts 58, however, will remain in the open position until the finger manipulator is released, at which time the arm 154 will also be released by the arm 158 of the finger manipulator 102 so 25 that it will be impossible to hold the contacts 30 closed by the use of the finger manipulator 102. This will prevent the refrigerating system from being forcibly operated under overload conditions when the ratchet wheel has released the slide plate 144. 35

In Fig. 4 I have provided a chart or graph in which the movement of the bellows follower lever at the bellows point is plotted along the horizontal scale and the effective pressure in pounds at the bellows point is plotted in the vertical direction. The bellows may be assumed as having an effective area of about one square inch so that this vertical scale will also represent the gas pressure within the bellows 24. Under ordinary circumstances the main spring 68 and the differential screw 64 are set so that the switch will be closed when the bellows is compressed and the bellows follower lever is moved upwardly, with reference to Fig. 1, from its extreme lower position a distance of .046 inch. The switch will open 50 when the bellows and bellows follower lever move downwardly about .025 of an inch to a position of .021 inch.

In Fig. 4, the line marked "Bellows" indicates the inherent spring force of the bellows which is 55 plotted as being negative pressure since it tends to push the bellows follower lever 38 downwardly. The two lines marked "Toggle" indicate the force of the toggle spring during the movement of the bellows and bellows follower lever. This force 60 changes from positive to negative when the switch cuts on or closes and changes from negative to positive when the switch cuts out or opens. The force provided by the main spring is plotted by the line which is designated as "Main spring 65 with cancel spring". This is a positive force which increases with the expansion of the bellows and movement of the bellows follower lever. This main spring is required to be strong enough to oppose the force of the bellows plus the force of 70 the gas pressure within the bellows plus the force of the toggle spring. However, in order to do this, the main spring would have to be adjusted to the strength or pull indicated by the dotted line upon the chart and marked "Main spring 75

without cancel spring". As shown in the chart, it would require about 3.6 lbs. or 3.7 lbs. gas pressure within the bellows to open the switch.

In the lower left hand corner of the chart in Fig. 4 is a curved line which designates the pressure temperature curve of sulphur dioxide, which for the purposes of illustration, is the gas used in the bellows and thermostat bulb. However, other gases such as methyl or ethyl chloride or difluorodichloromethane may be used if desired. Beneath this curved line is a temperature scale. The point 3.6 or 3.7 upon the pressure temperature curve of sulphur dioxide represents upon the temperature scale about 23° F. When the switch moves to cut-on position, the main spring is stretched further and then has an effective pull of 12 lbs. Under ordinary circumstances, this plus the force of the toggle spring must be balanced by the force of the bellows plus the gas pressure within the bellows, in order to make the switch close. However, the force of the bellows decreases as shown by the chart so that a greatly increased gas pressure of 10 lbs. is required to close the switch. This corresponds to a temperature of about 36° F. or 37° F. which makes a switch differential of about 13° or 14° F.

The main spring necessarily has a high rate because of the small space provided. In order to provide an effective temperature adjustment by the knob 14, it is difficult from the practical standpoint to materially reduce the rate of the main spring within a switch structure of such a small size. This switch is about four inches long, two inches wide and one and one-half inches deep. In Figs. 1, 2 and 3, each dimension is doubled in size. In order to reduce the differential of the switch, it is, therefore, necessary to find some means for reducing the rate of either the bellows, the main spring or both. However, it is not possible to conveniently reduce the rate of the main spring or of the bellows.

I, however, have found a way to obtain the same effect. I do this by providing a tension spring 170 which extends into a slot 172 provided in the bellows follower lever 38 and is hooked to an aperture located at the closed end of the slot. The other end of this tension coil spring is hooked in the eye of a threaded pin 174 which is threaded within a nut 176 mounted upon the opposite side 50 of an L-shaped bracket 178 which in turn is riveted to a projection of the arm 34. It should be noted that the center line of this spring extends above the pivot point of the main lever 38 and the spring extends from the main lever 38 at a 55 slight angle thereto. Thus, when the bellows 24 are collapsed to the cut-off position, the spring 170 exerts its maximum force aiding the main spring 68. At this time, the bellows 24 also exerts its maximum inherent spring force. As the 60 bellows expands, the inherent spring force of the bellows weakens, as shown in the chart, while at the same time the spring 170 provides an effective force substantially equal and opposite to the inherent spring force of the bellows.

In Fig. 1 I have located the screw 174 and made a spring 170 of such a rate so that it is substantially equal and opposite to the inherent spring force of the bellows through its range of movement between the cut-off and cut-on points. In fact, it is substantially equal and opposite throughout the movement of the bellows. I, therefore, call this spring a bellows cancel spring because it cancels in effect the inherent spring force of the bellows. By adding this bellows cancel spring, it is possible to reduce the force of

the main spring. It will be seen that when no cancel spring is used, it is necessary to provide a main spring which has eight pounds of force at the cut-off point and twelve pounds force at the cut-on point. By employing the bellows cancel spring 170 it is possible to reduce the force of the main spring 68 at the cut-off point to 4.6 lbs. while this same spring would have a force of only about 8.6 lbs. at the cut-on point.

The force of the bellows plus the force of the gas pressure must be sufficient to equal the force of the toggle plus the force of the bellows cancel spring, plus the force of the main spring when a cancel spring is used. When no cancel spring is used, the bellows force plus the gas pressure must equal the force of the toggle plus the main spring. However, since the bellows cancel spring has a negative rate; that is, its force is reduced as the bellows expands, it reduces the force normally required of the bellows and gas pressure to move the switch to cut-on position by the amount that the force of the bellows cancel spring is reduced. Since the bellows cancel spring has reduced the force about 1.2 or 1.3 lbs., a lesser gas pressure is required. Thus, the chart shows when a cancel spring is used is about 8.8 lbs. This corresponds to about 33° F. so that the differential of the switch by the use of this cancel spring has been reduced 3°.

However, since the main spring need not supply so great an amount of force, its rate may also be reduced slightly if desired. Furthermore, the bellows cancel spring may be located at other angles and may have a greater force so that it would provide a more variable negative rate so as to not only cancel the inherent spring force of the bellows but also to cancel a portion of the force of the main spring so that in effect it would reduce the rate of the main spring. Thus, by employing this bellows cancel spring, I am able to considerably lower the differential of the switch without changing the relationship, size and force of any of the elements of the switch, but merely by the addition of the bellows cancel spring which may not only be used to cancel out the inherent spring force of the bellows, but also to reduce the effective rate of the main spring and thus to considerably reduce the differential of the switch.

While the form of embodiment of the invention as herein disclosed, constitutes a preferred form, it is to be understood that other forms might be adopted, all coming within the scope of the claims which follow.

What is claimed is as follows:

1. A control means including a pressure operated diaphragm means having an inherent natural resilient resistance to movement from a neutral position, a means to be operated by said diaphragm means, and cancelling means providing a force substantially equal and opposite to said inherent natural resilient resistance of the diaphragm means for substantially cancelling said resilient resistance.

2. A control means including a pressure operated diaphragm means having an inherent natural resilient resistance to movement from a neutral position, a means to be operated by said diaphragm means, and spring means providing a force substantially equal and opposite to said inherent natural resilient resistance of the diaphragm means for substantially cancelling said resilient resistance.

3. A control means including a pressure op-

- erated diaphragm means having an inherent natural resilient resistance to movement from a neutral position, a means to be operated by said diaphragm means, and resilient over-center means providing a force substantially equal and opposite to said inherent natural resilient resistance of the diaphragm means for substantially cancelling said resilient resistance.
4. A control means including a pressure operated diaphragm means having an inherent natural resilient resistance to movement from a neutral position, a means to be operated by said diaphragm means, a snap acting means connecting said means to be operated and said diaphragm means, and means acting upon said diaphragm means providing a force substantially equal and opposite to said inherent natural resistance of said diaphragm means for cancelling said natural resistance.
5. A control means including a pressure operated diaphragm means, a switch means operated by said diaphragm means, means for limiting the expansion of the diaphragm means, said diaphragm means having an inherent spring force decreasing with expansion of the diaphragm means in a direction aiding the expansion of the diaphragm means, and a spring means providing throughout the limited expansion of the diaphragm means a decreasing positive resistance with the expansion of the diaphragm means opposing the expansion of the diaphragm means.
6. A control means including a pressure operated diaphragm means, a switch means operated by said diaphragm means, means for limiting the expansion of the diaphragm means, said diaphragm means having an inherent spring force decreasing with expansion of the diaphragm means in a direction aiding the expansion of the diaphragm means, a yielding means providing an increasing resistance with the expansion of the diaphragm means opposing the expansion of the diaphragm means, and a yielding means providing throughout the limited expansion of the diaphragm means a positive decreasing resistance with the expansion of the diaphragm means opposing the expansion of the diaphragm means.
7. A control means including a pressure operated diaphragm means, a switch means operated by said diaphragm means, means for limiting the expansion of the diaphragm means,

and a yielding means providing throughout the limited movement of the diaphragm means a decreasing positive resistance with the expansion of the diaphragm means opposing the expansion of the diaphragm means.

8. A control means including a pressure operated diaphragm means, a switch means operated by said diaphragm means, means for limiting the expansion of the diaphragm means, and a yielding spring means providing a decreasing positive resistance to the expansion of the diaphragm means opposing the expansion of the diaphragm means throughout the limited expansion of the diaphragm means.

9. A control means including a pressure operated diaphragm means, a switch means opened and closed at certain positions of movement of the diaphragm means, and a yielding means providing a decreasing resistance with the expansion of said diaphragm means from one of said certain positions to another, said yielding means providing a positive resistance to the expansion of said diaphragm means between said positions.

10. A control means including a set of switch contacts, a diaphragm means for operating said contacts, a second set of switch contacts located adjacent said first set of contacts, and magnetic means located between said sets of contacts for creating a magnetic field enveloping both of said sets of contacts.

11. A control means including a set of switch contacts, a diaphragm means for operating said contacts, a second set of switch contacts located adjacent said first set of contacts, and electromagnetic means located between said sets of contacts and energized by electric energy flowing through one of said sets of contacts for creating a magnetic field enveloping both of said sets of contacts.

12. A refrigerator control to be mounted within the compartment to be cooled of a refrigerator cabinet, said control including a casing containing a diaphragm means, a switch mechanism operated by the diaphragm means, an electric circuit controlled by said switch means, and means for preventing corrosion of the mechanism in said casing including an electric heater electrically connected to said electric circuit and controlled by said switch mechanism for heating the refrigerator control.

ALBERT O. GROOMS.
